UNITED STATES PATENT OFFICE.

JAMES ALFARD BAIN, OF ALTOONA, ALABAMA.

DELIVERY-CABINET.

1,195,129.

Specification of Letters Patent. Patented Aug. 15, 1916.

Application filed December 23, 1914. Serial No. 878,796.

To all whom it may concern:

Be it known that I, JAMES A. BAIN, citizen of the United States, residing at Altoona, in the county of Etowah and State 5 of Alabama, have invented certain new and useful Improvements in Delivery-Cabinets, of which the following is a specification.

My invention relates to an improved delivery cabinet and refrigerator combined, 10 and more particularly to a cabinet designed for holding bottles or packaged liquid in order that the same may be cooled and maintained in such cooled condition pending consumption.

15 The objects of the invention will become manifest as the description proceeds.

In describing my invention in detail, reference will be had to the accompanying drawings wherein like characters designate 20 like or corresponding parts throughout the several views, and in which:

Figure 1 is a side elevation of the cabinet; Fig. 2 is a top plan view, partly broken away; Fig. 3 is a section on the line 3—3 of Fig. 2; Fig. 4 is a section on the line 4—4 of Fig. 2; Fig. 5 is a horizontal sectional view of the cabinet, parts being shown in elevation; Fig. 6 is a section on the line 6—6 of Fig. 5; Fig. 7 is a view similar to Fig. 3, 30 partly broken away, a bottle having been extracted through operation of the delivery means; and Fig. 8 is an enlarged section on the line 8—8 of Fig. 2.

Referring now to the drawings by numerals, 1 designates the side walls, 2 the bottom, and 3 the top of my improved cabinet, the latter being open as indicated at 4 to a refrigerator compartment designated 5 mounted on the cabinet and provided with 40 a removable refrigerator top 6. A receptacle or container 7 is arranged in the compartment 5, strips 8 acting as a support therefor.

As shown to advantage in Fig. 5, the cabinet is partitioned as indicated at 9 to form 45 substantially semicircular passage ways or guide ways within which the packaged liquid or bottles are arranged, the partitions 9, except the outermost, terminating at a point in spaced relation to the forward wall 10 of the cabinet whereby to leave a space 10 within which a movable carrier 11 is operated. The outermost partition, as shown, 50 is extended forwardly of the remaining par-

titions and at a right angle thereto as indicated at 12, the extended portion forming 55 a guide for the carrier 11.

The bottles (indicated by the dotted lines in Fig. 5) are arranged within the guide ways formed by the partitions 9 in engaging proximity, and are adapted, through operation of a lever 13 to force the bottle to be extracted into a position whereby such extraction may take place. Preferably, each guide way is adapted to contain a different beverage, for instance, guide way A may 60 contain ginger-ale, the guide way B, coca-cola, the guideway C, sarsaparilla, etc., such arrangement obviating the necessitating of a search and insuring delivery of the beverage desired. Although but five guide ways 65 have been illustrated, the same being designated respectively A, B, C, D and E, it is to be understood that a less or greater number may be used if desired.

At the forward end of guide way A and 75 at the juncture of the space 10 and said guide way, the bottom 2 of the cabinet is cut away as indicated at 14 to form an opening beneath which a closed end cylinder 15 is disposed, the cylinder containing a piston 80 16 which acts as a cushioning means for the extracting or delivery mechanism to be hereinafter fully described. The piston 16 or rather the plunger, is mounted on a rod 17 connected at its opposite end to a movable 85 tray or platform 18 normally disposed to fit the opening 14 and to extend upon the same horizontal plane as the floor or bottom of the cabinet 2. From one side of the platform 18, a vertical arm 19 extends, the said arm, with 90 a rack bar 20 and a connecting portion 21 forming a movable extractor of an inverted U-shape. The extractor is arranged to straddle the forward wall of the cabinet. It will be noted that the rack bar extension 95 20 of the extractor is of a length sufficient to provide for movement of the platform 18 from the position shown in Fig. 3 to the position shown in Fig. 7, the movement being vertical and from a position upon the same 100 horizontal plane as the bottom 2 of the cabinet to a position somewhat above the horizontal plane of the top 3, an opening 22 in the said top permitting of such movement. As the actuating medium for the extractor 105 21, I provide a gear 23 so mounted as to be

rotatable through operation of a crank arm 24. The teeth of the gear mesh with the rack as shown.

Carrier 11 operates in a substantially horizontal plane, the carrier being movable from the position in which it is shown in Fig. 5 to a position in line with the partition dividing passage ways A and B, such movement providing for a corresponding bodily movement of the bottles of passage way E to a position in line with passage way A or onto the platform 18 where they may be extracted through manipulation of lever 24. The bottles of passages B, C and D are also moved into proper place upon the platform 18 through movement of the carrier 11, the latter operating in the space 10 and being of such size as to receive the bottles, one at a time, so as to later provide for extraction, singly. The operating means for the carrier 11 consists of a lever 25 pivoted as at 26 intermediate its ends, the lever operating in an opening 27 of the cabinet top and being connected to the carrier through the medium of a link 28 pivoted at one end to said lever and at its opposite end to the carrier 11, the arrangement causing the carrier to be bodily moved as hereinbefore described upon movement of the lever back and forth.

To insure automatic operation of the cabinet, a bottle must be replaced for each bottle removed, this for the reason that the passage ways must be filled in order that the bottles may be moved, one at a time, onto the platform 18. Movement of the bottles from between the partitions 9 to the space 10 is effected by means of the lever 13, the latter being pivoted as at 14' at its lower end and provided, intermediate its ends with an angular extension 15' so situated with respect to the forward wall of the cabinet as to extend through an opening 16' therein and to engage the bottles of the passage ways into which the extension 15' extends. An independent lever 13 is provided for each passage way in order that the bottles therein may be moved as occasion demands. Directly above each passage way and at a point adjacent the extension 15', I provide openings 29, such openings allowing the bottles to be placed in the cabinet after each extracting operation. The openings 29 are normally closed by a hinged cover 30 which will preclude the admission of warm air to the cabinet.

The manner in which the bottles are extracted having been fully described, I shall now proceed with the description of the novel means utilized to remove the bottle caps subsequent to the extracting operation. Directly over the opening 22 in the cabinet top 3, and upon the same horizontal plane as the top 6 of the refrigerator compartment, I provide an arm 30 rigid with the refrigerator, and braced as indicated at 31.

An opening 32 is formed in the forward end of the arm, the opening being in line with the opening 22 to receive, in the raised position of the platform 18, the neck of the bottle acted on, the opening forming a guide means to direct the bottle cap mounted on the bottle neck into the opening 33, the latter being formed in a movable hinge block 34 which forms a part of the bottle cap remover. The said remover in addition to the block 34 comprises a stationary block 35 also provided with an opening 36 into which the bottle neck extends. The hinge block 34 is recessed as at 37 to provide for the reception of a stationary cap engaging member 38 and a movable cap engaging member 39, the latter being spring actuated as indicated at 40 and maintained against displacement by a strip 41 rigid with the movable block. Both the stationary and the movable cap engaging members are provided with co-acting biting edges which are adapted to engage the underneath side of the bottle cap in a manner shown to advantage in Fig. 8, such engagement causing the cap to be bodily removed from the bottle through upward movement of the block 34. Such upward movement of the block is effected automatically subsequent to an extracting operation through manipulation of the lever 24. A lifting arm 42 is mounted on a rotatable disk 42' at a point adjacent its periphery or as indicated at 43, the said arm being engageable with the movable block 34. Disk 42' is rotatable through operation of lever 24, and upon a reverse or continued rotation of said disk it is evident that arm 42 will exert an upward pressure on the block to provide for a removal of the bottle cap as hereinbefore set forth. Movement of the arm 42 is so timed as to cause the upward pressure on the block to be exerted only subsequent to the movement of the bottle automatically into a position whereby members 38 and 39 will engage the bottle cap. The beveled co-acting terminals of the members 38 and 39 will facilitate movement of the bottles into proper place. To return the block 34 to its normal position subsequent to a bottle cap removing operation, I provide a spring 44.

In use, receptacle 7 is adapted to contain ice or a like cooling medium. The passage ways A, B, C, D and E are adapted to be filled with bottled beverages, each passage way containing a different beverage. Should it be desired that a bottle of ginger-ale be delivered, the ginger-ale being placed in the passage way A, it is evident that such delivery may be effected in the following manner, to wit: Lever 13 is first actuated to bodily move the bottles in the passage way A sufficient to cause the foremost bottle to move onto the platform 18, the latter being within the opening 14 which is alined with

said passage way and situated in the space 10 open thereto. A bottle having been thus positioned on the platform 18, lever 24 is operated to rotate the gear 23. Rotation of 5 the gear will bodily move the extractor 21 (of which the platform is a part) causing the bottle to be elevated into the position shown in Fig. 7, the bottle passing through the opening 22 in the cabinet top and the 10 neck of the bottle being guided by the openings 32, 36 and 33 until the cap of the bottle is properly engaged by the members 38 and 39. The spring 40 will contract automatically as the bottle cap is forced into engagement 15 with the member 39 and, as the cap is forced above said member, the said spring will automatically return the member into engagement with the underneath side of the cap or so position the member as to permit of a bottle cap extraction upon continued movement of the disk. As suggested, continued or a reverse movement of the disk will cause arm 42 to exert upward pressure on block 34 against tension of spring 44, such movement 20 of the block causing the cap to be removed with facility and ease. The bottle cap having been removed, lever 24 is operated in a reverse direction so as to permit platform 18 to recede, the piston 16 acting 25 as a cushion for the platform during its receding movement. It is to be understood of course that the bottle is withdrawn from the platform prior to the receding action. After each delivery, a fresh bottle is placed in 30 the passage way from which the bottle last acted on was removed, the bottle being replaced through one of the openings 29; the said bottle having been replaced, it is evident that the extracting mechanism may be 35 again operated as hereinbefore described. From the foregoing, taken in connection with the accompanying drawings it will be noted that the delivery and cap removing operation are both effected through operation 40 of the lever 28; that operation of lever 25 is unnecessary when it is desired to deliver the beverage placed in the passage way A; and that lever 25 need only be actuated to position the bottled beverage onto 45 the platform, the movement of the bottled beverage being within the space 10 therefor. In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various 50 minor changes in details of construction, proportion and arrangement of parts may be resorted to, when required, without sacrificing any of the advantages of my invention, as defined in the appended claims. 55 Having thus fully described my invention,

what I claim as new and desire to secure by Letters Patent, is:—

1. The combination, of a delivery cabinet for bottled goods, and a mechanism to remove the bottle-tops during delivery. 70
2. In a delivery cabinet for bottles, a means to horizontally feed the bottled goods, a means to deliver the bottled goods into a position for individual extraction, a means to engage with and elevate the bottled goods to a position without the cabinet, and a means disposed in the path of the thus elevated bottles to remove the bottle caps therefrom. 75
3. In a delivery cabinet for bottles, guide ways within which the bottles are arranged, a single extracting mechanism, means to advance the bottles within each guide way, means to move the bottles subsequent to advancement into engaging proximity with the extracting mechanism, means to vertically move the extracting mechanism with a single bottle thereon, and means to cushion the extracting mechanism in returning to its normal position subsequent to an extracting operation. 80
4. In a delivery cabinet for bottled goods, partitions dividing the cabinet into a plurality of parallel horizontally feeding guide ways, an individual means operating in each guide way to advance the bottled goods contained therein, a means mounted to operate transversely of the several guide ways to deliver the advanced bottles into a position for subsequent extraction, and a means operable to engage with and elevate the thus delivered goods to a position without the cabinet. 95
5. In a delivery cabinet for bottled goods, a means operable to deliver the goods individually into a position permitting subsequent extraction, a platform movable to elevate the goods from a position within to a position without the cabinet, operating mechanism including a gear and ratchet to move said platform, and a means to cushion the return movement thereof. 100
6. In a delivery cabinet for packaged liquids, the combination with mechanism for advancing the packages acted on into a position to be extracted, extracting mechanism comprising a platform onto which the packages are moved during advancement, a rack bar movable with the platform, and means engaging the rack bar to move the platform vertically in an extracting operation. 115
7. In a delivery cabinet for bottles, means to extract the bottles singly from the cabinet, and means operating automatically during an extracting operation to remove the bottle caps from the bottles. 125
8. In a delivery cabinet for bottles, mechanism to advance the bottles singly into a position to be extracted, mechanism operable 130

to lift the bottles singly from a position within to a position without the cabinet, means operating automatically to remove the bottle caps from the bottles during an extracting operation, and mechanism operating automatically to control movement of the ejecting mechanism subsequent to an ejecting operation.

9. In a delivery cabinet for bottles, the combination with the mechanism for extracting the bottles singly from the cabinet, of a bottle cap remover arranged in the path of movement of the bottles acted on, and means operable through movement of the extracting mechanism to actuate the remover immediately subsequent to the extraction of the bottles from the cabinet.

10. In a delivery cabinet for bottles, the combination with the extracting mechanism for removing the bottles singly from the cabinet, of a bottle cap remover operating in conjunction with the cabinet, the said remover comprising a stationary and a relatively movable member, means carried by one of said members to engage the bottle cap, and means operable during an extracting operation to engage said movable member for actuating the same to remove the bottle cap immediately subsequent to an extraction of the bottle, as and for the purpose set forth.

11. In a delivery cabinet for bottles, a plurality of guide ways for the bottles acted on, means to advance the bottles into a position to be singly extracted, an extractor comprising a platform onto which the bottles are moved immediately previous to an extracting operation, a vertical rack bar movable with the platform, means to cushion the platform during its movement, means operable to engage the rack bar and move the platform vertically to extract the bottle

mounted thereon, and mechanism operating automatically through movement of the extracting operation to remove the bottle cap from the extracted bottle.

12. In a delivery cabinet for bottles, the combination with a refrigerating compartment, of a plurality of guide ways arranged to extend within said compartment, means to advance the bottles of each guide way, extracting mechanism, means to move a single bottle into engaging proximity with said extracting mechanism, mechanism operable to elevate the extracting mechanism to remove the bottle mounted thereon from within the cabinet, and means operating automatically to remove the bottle cap from the bottle during its extraction.

13. In a delivery cabinet for bottles, extracting mechanism, a plurality of guide ways terminating at a point adjacent said extracting mechanism, means to advance the bottles within the guide ways, mechanism to move the bottles laterally of the guide ways and into engaging proximity with said extracting mechanism, and means to control movement of said mechanism subsequent to movement of the bottle acted on into engagement therewith.

14. The combination, of a delivery cabinet for bottled goods, a means to successively elevate the bottles from a position within to a position without the cabinet in the process of delivery, and means to engage with and remove the bottle tops from the bottle during movement in the manner stated.

In testimony whereof I affix my signature in presence of two witnesses.

JAMES ALFARD BAIN.
